UNITED STATES PATENT OFFICE.

LOUIS HAMMER, OF OLDS, ALBERTA, CANADA.

AUTO PULL-OUT.

1,343,625.

Specification of Letters Patent. Patented June 15, 1920.

Application filed January 29, 1918, Serial No. 214,389. Renewed April 28, 1920. Serial No. 377,420.

To all whom it may concern:

Be it known that I, LOUIS HAMMER, a citizen of the Dominion of Canada, residing at Olds, in the Province of Alberta, Canada, have invented a new and Improved 5 Auto Pull-Out, of which the following is a specification.

My invention has reference to improvements in means adapted to be readily applied to the conventional types of automobile chassis and capable of being quickly adjusted for utilizing the motor engine for pulling the vehicle out of ruts, mud, holes, etc.

15 More especially my present invention has reference to that type of "pull outs" in which is included a drum on which the anchored or pull cable is wound, for example, as illustrated in my Patent No. 1,256,791, dated February 19, 1918.

Among other objects, my present invention seeks to provide a mechanism for the purposes stated of a simple and inexpensive construction, in which the parts are individually designed and adapted to be so combined that the said mechanism may be quickly applied to the chassis of all of the ordinary types of motor vehicles, capable of being instantaneously adjusted into a 25 clutched engagement with the vehicle motor shaft or released from such shaft and which serves its intended purposes in a thorough, practical and efficient manner. Again, in my present invention, I have provided an 30 improved power transmission for driving the cable wind-up with adjustable means for holding the said transmission to the driving position for applying the desired power to the cable wind-up devices and 35 which can be quickly shifted for permitting the removal of the said transmission and the substitution therefor of a direct drive shaft section carrying a belt or chain pull for coupling a drive or chain belt therewith 40 for transmitting the power for running such light machinery that constitute parts of modern farm equipment. Another and important feature of my present invention lies 45 in the improved construction of the power transmission devices, including a direct driv-

ing connection with a jack shaft and shift-able gearing on the jack shaft adapted to be freely shifted into engagement with the winding drum when it is desired to wind up the pull cable and for being moved out 55 of mesh with the said drum to permit of the free rotation of the drum when playing out the cable therefrom, for attaching it to an anchor post.

With the above and other minor objects 60 in view, that will hereinafter appear, my present invention is an improved "auto pull out mechanism" that embodies the peculiar features of construction and novel combination of parts fully set out in the following 65 description and specifically stated in the appended claims and as illustrated in the accompanying drawings, in which:

Figure 1 is a plan view of my present construction of "pull out mechanism", the 70 parts being in the operative position, a cranking lever being indicated as an applied portion thereof, in dotted lines.

Fig. 2 is a longitudinal section thereof on the line 2—2 of Fig. 1, the said mechanism being shown as in a coupled position with the engine shaft for driving the cable carrying drum.

Fig. 3 is a plan view of my present invention, the worm or transmission shaft being shown out of clutch with the engine shaft, and the jack shaft as uncoupled from the winding drum, the latter being now free to permit of pulling out the cable for making the anchor connection, the hinged cap 80 that closes over the transmission worm gear being shown as raised.

Fig. 4 is an end view of the transmission shaft, the gear that connects said shaft and the jack shaft and the casing that constitutes a support for the transmission shaft.

Fig. 5 is a transverse section taken on the line 5—5 of Fig. 1, of one of the end brackets that connects with the chassis and in which one of the outer ends of the drum 95 and the jack shafts journal, the said bracket being shown in side elevation.

Fig. 6 is a detail perspective view of one of the said brackets.

Fig. 7 is a diagrammatic plan view that 100

5 illustrates a supplemental transmission shaft, with a transmission power pulley, the said shaft forming a substitute for the worm transmission shaft when it is desired to utilize the motor shaft for driving wood sawing or other like machinery.

10 Referring now more particularly to Figs. 1 and 2 of the drawings, 1—1 designate the front portions of the automobile chassis members to each of which is attached one of a pair of opposing brackets 2—2, one of which is shown in detail in Fig. 6, each bracket including a top horizontal bar 20 having suitable apertures 21—21 for receiving 15 the bolts 22 that attach the said bracket to the chassis members, as clearly shown in Fig. 5.

20 Each bracket 2 includes a pair of pendent hanger members 23—24 that are braced by a connecting web 25 and the said bracket members 23 each have a bearing aperture 26 and the members 24 a vertically elongated slot 27, the purpose of which will presently appear.

25 In my patented structure above referred to, the cable winding means includes a shaft centrally equipped with a driving gear that meshes directly with the worm on the transmission shaft and two drum sections keyed 30 upon the said shaft.

35 In my present construction, I use but a single drum 3 that extends practically the full width between the opposite chassis members 1—1 and it is loosely mounted on a shaft 4 whose opposite ends journal in the bearing apertures 26 in the bracket members 23.

Each end of the drum has keyed, or otherwise fixedly attached thereto, a gear 30.

40 By using a single drum, as shown, a long length of pull cable may be carried thereon, it being understood that the inner end of such cable, in practice, is made fast to the drum and further by loosely mounting 45 the cable drum on the shaft, when the said drum is freed from connection with the power transmission, as will be presently more fully understood, the outer or free end of the pull cable may be readily "played" 50 out from the drum when it is desired to anchor the cable without disturbing any of the other parts that constitute my present invention.

55 7 designates a jack shaft in parallelism with and disposed to the rear of the drum shaft and is best shown in Figs. 2 and 5, by reference to which it will be seen that the opposite ends of the jack shaft 7 are journaled in bearing boxes 8—8 mounted in 60 each of the slots 27 of the bracket hangers 24 and the said boxes 8 have vertical adjustment in said slots 27 and are held to their adjusted positions by clamp screws 28—28, as shown.

65 In my present construction, the shiftable transmission devices, when coupled with the engine shaft, instead of being geared directly with the drum shaft, as in my patented structure above referred to, are arranged for transmitting an indirect and increased 70 power to the said drum shaft and to such end the transmission shaft section 5 is loosely journaled in the ends 60—60 of the housing or casting which is best shown in Figs. 1, 2 and 3.

75 The casting or housing 6 is formed with pendent side brackets 61—61 that are supported on the jack shaft 7 which passes through apertures 62—62 in the said brackets.

80 The casting 6 also has apertured ears 63—63 at one side connected by a hinged pintle 64 to which a housing or cover 65 is hinged for being swung to the vertical position shown in Fig. 4. When placing the 85 transmission shaft section 5 into or removing it from the operative position, the cover 65, when the parts are operatively assembled, is held to the closed position by screws 66 that engage registering apertured ears 90 on the cover and the housing body.

85 The worm gear, in my present structure, is keyed to the shaft 5 to turn therewith and it meshes with and transmits motion to a gear 70 keyed to the jack shaft 7 and the 95 said motion is transmitted to the drum shaft through the gears 71—71 on the opposite ends of the jack shaft 7 hereinbefore referred to and which are made fast to the shaft by clamp screws 72—72 that take 100 through the gear hubs 73—73.

95 The gears 71—71, when the parts are in the operative or cable wound-up adjustment, mesh with the drum gears 30—30, as shown in Fig. 1. When, however, it is desired to pull the cable from the drum for anchoring, the gears 71—71 are shifted to the position shown in Fig. 3.

100 11—11 designate brace rods that connect with the chassis members 1—1 and the opposite sides of the housing 6.

115 12 indicates a slotted clutch sleeve on the outer end of the engine shaft 9. 13 indicates the usual clutch pin and 55 the slot in the end of the transmission shaft 5 which engages the said sleeve and the pin when the shaft is slid back and clutched with the engine shaft, as shown in Figs. 1 and 2.

120 In my present construction of "pull out mechanism", a lever 14 is pivoted at one end on a bracket 66 on the housing 6, and the said lever straddles and engages the annular groove 15 of a disk fixedly connected to the shaft and whose front end terminates in a ratchet face 15a.

125 For shifting the transmission shaft into a clutched engagement with the engine shaft, the lever 14 is adjusted to the position shown

in Fig. 1 and for throwing the transmission mechanism out of engagement with the engine shaft, the said lever is swung out in the position shown in Fig. 3.

5 17 designates a cranking lever indicated in dotted lines in Fig. 1 whose inner end has a ratchet surface for coupling with the ratchet 15^a on the disk 15.

From the foregoing description, taken in 10 connection with the drawings, the complete construction, the manner of its use and the advantages of my improved pull out mechanism will be readily apparent.

When attached to motor vehicles having 15 self-starters, the adjustment of the lever 14 to the position shown in Figs. 1 and 3 provides for putting the "pull out mechanism" into or out of operative connection with the engine shaft, the crank lever being utilized 20 when the attachment is secured to machines that are not self-starters.

It will be noticed by referring to Figs. 2 and 3, there is sufficient play in the housing 6 for shifting the shaft 5 with its gear 50 25 to the clutching and released positions and when shifted to the clutch position the connection of the gears 50 and 70 is such that so long as the engine is running, the gear 50 will be held up to the active or clutched 30 position shown in Fig. 1.

When it is desired to use the vehicle motor for farm work, that is,—driving small machinery—the transmission shaft 5 is removed and a plain shaft 18, shown in Fig. 35 7, is substituted therefor, and when the latter is used a transverse front bearing bar 80 is attached to the opposite chassis members 1—1.

In practice, a hood π covers the working 40 parts of my "pull out mechanism" and the latter is hingedly attached to the front of the radiator hood, as indicated in dotted lines in Fig. 5.

What I claim is:

45 1. In a pull out mechanism for motor vehicles, the combination with the chassis frame and the motor driven shaft; of a housing having opposite end bearings in alinement with the engine shaft, a transmission shaft section removably supported on the said end bearings and in alinement with the engine shaft, the said transmission shaft section and the engine shaft having engaging clutch portions, the transmission shaft section having longitudinal movement in the said end bearings of the housing, and a device mounted on the housing and operatively connected to the transmission shaft by means of which device the 50 transmission shaft can be moved into operative connection with the engine shaft and held there.

2. In a pull out mechanism for motor vehicles, the combination with the opposite

5 side members of the chassis frame and the motor driven shaft; of a cable receiving and wind-up drum mounted between the opposite side chassis members, a housing having opposite end bearings in longitudinal alinement with the engine shaft, a transmission shaft section adapted to rest in the housing and journal on the end bearings thereof, a driving gear on the said transmission shaft, the said shaft being longitudinally slidable on the end bearings, 70 said transmission and the engine shaft having interlocking clutch portions and gearing that joins the transmission shaft section and the winding drum.

3. In an automobile having a chassis 80 frame and a motor driven engine shaft; a cable winding drum mounted between the opposite front members of the chassis frame, a jack shaft mounted between the said frame members and in parallelism with the drum, said drum and the jack shaft carrying intermeshing gears, a transmission shaft section, a support located between the opposite chassis members having opposite end bearings in longitudinal alinement 90 with the engine shaft that form the supports for the transmission shaft section, the latter and the engine shaft having interengaging clutch ends, means for shifting the transmission shaft section into a clutched 95 connection with the engine shaft, and intermeshing gears on the jack shaft and the transmission shaft section.

4. In an automobile having a chassis 100 frame and a motor driven engine shaft; a cable winding drum mounted between the opposite front members of the chassis frame, a jack shaft mounted between the said frame members and in parallelism with the drum, said drum and the jack shaft carrying intermeshing gears, a transmission shaft section, a support located between the opposite chassis members having opposite end bearings in longitudinal alinement 105 with the engine shaft that form the supports for the transmission shaft section, the latter and the engine shaft having intermeshing clutch ends, means for shifting the transmission shaft section into a clutched connection with the engine shaft, 110 intermeshing gears on the jack shaft and the transmission shaft section, the gears on the jack shaft being endwise adjustable whereby to disconnect the jack shaft and the winding drum at times.

5. In an automobile having a chassis 115 frame and a motor driven engine shaft; a cable winding drum mounted between the opposite front members of the chassis frame, a jack shaft mounted between the 120 said frame members and in parallelism with the drum, said drum and the jack shaft carrying intermeshing gears, a transmis-

mission shaft section, a support located between the opposite chassis members having opposite end bearings in longitudinal alignment with the engine shaft that form the supports for the transmission shaft section, the latter and the engine shaft having interengaging clutch ends, means for shifting

the transmission shaft section into a clutched connection with the engine shaft, intermeshing gears on the jack shaft and the transmission shaft section, the said jack shaft having vertical adjustment relatively to the transmission shaft.

LOUIS HAMMER.
